UNITED STATES PATENT OFFICE.

CHARLES L. GEORGE, OF FINDLAY, OHIO, ASSIGNOR TO THE BUCKEYE TRACTION DITCHER CO., OF FINDLAY, OHIO, A CORPORATION OF OHIO.

DITCHING MACHINE.

Application filed December 30, 1927. Serial No. 243,534.

This invention relates to a ditching machine, with special reference to the cutting wheel and the means for driving the same.

In machines of the type to which my invention relates, the cutting and digging members are carried by two wheel rims which are supported in spaced parallel relation for rotation about a relatively fixed axis. The means for driving these rims usually comprises a series of cogs carried by the respective rims and driving gears in mesh therewith. In replacing these intermeshing parts after they become worn or broken, or when assembling a new machine, difficulty has been experienced in obtaining the proper relation between them in order that there may be no binding action and in order that the drive may be equal at opposite sides of the wheel.

The object of the present invention is to overcome the above mentioned difficulties and to obtain freely operable, uniform and equal driving relations between the two rims and the power shaft.

The specific construction of the invention, in its present embodiment, together with the advantages resulting therefrom, will be more particularly described with reference to the accompanying drawing, in which—

Figure 1 is a side elevation of a portion of a ditching machine to which the invention is applied.

Fig. 2 is a sectional view taken substantially on the line 2—2 of Fig. 1.

Fig. 3 is a detail view of one of the driving gears and the means for mounting the same.

The invention is illustrated in connection with a ditching machine having a frame 5 on which is a revolvably mounted cutting wheel having oppositely disposed rims 7. Secured to these rims are annular strips 8 to which the cutting and digging members 9 are secured. Each rim 7 revolves on idle rolls 10, one of which is shown in Fig. 1.

Associated with each rim is a driving gear 11 meshing with cogs 12 carried by the rim. The driving gear is secured to a sleeve 13 mounted in a journal box 14 at the side of the frame 5. The driving sleeve 13 is provided with flanges 15 and 16 at opposite sides of the journal box.

The inner portion of each sleeve 13 is non-circular in cross section, preferably square as shown in Figure 3, and is formed with a

number of peripheral channels 17 in one of which a split collar 18 is mounted, this collar being bolted to the driving gear 11. Thus the driving gear is secured on the non-circular portion of the shaft and held against movement longitudinally thereof while the several channels 17 permit the gear to be adjusted for cutting wheels of different width.

Each sleeve 13 is driven by a sprocket wheel 19 mounted on the outer end thereof and bolted to the flange 15. A beveled gear 20 is also bolted to the flange and, through the medium of gearing 23, is adapted to drive a conveyor for carrying away the material which is removed from the ditch by the cutting wheel. A shaft 21 is mounted in the sleeves 13 and holds the same in alignment, the shaft being retained by heads 22 secured to opposite ends thereof. The sprocket wheels 19 are driven by sprocket chains 24 from sprocket wheels 25 and 26 respectively, mounted on a counter shaft 27. One of the sprocket wheels, as 25, is keyed to the counter shaft 27 while the other, as 26, is held by a retaining washer 28 on the shaft 27 and in toothed engagement with a sleeve 29 which is rotatably mounted on the shaft. The shaft 27 and sleeve 29, and consequently the sprocket wheels 25 and 26, are differentially driven by differential gearing 30 which has a ring gear 31 driven by a sprocket chain 32 from the main power shaft 33.

From the foregoing description it will be seen that the sprocket wheels 25 and 26, and consequently the driving gears 11, are differentially driven, thus permitting the gears 11 to adjust themselves automatically to the cogs 12 on the rims of the cutting wheel. This compensates for any inequalities in the rims, prevents any binding action due to unequal wear or unequal strain and insures a smooth and uniform drive under all conditions.

While I have shown and described the invention as applied only to one specific type of ditching machine it is to be understood that the invention is not limited to this specific construction but may be readily modified for use in connection with various other types of construction.

What I claim is:

1. In a ditching machine, a cutting wheel having two laterally spaced annularly toothed

members, a drive gear in mesh with each toothed member, said gears being relatively rotatable, and differential driving means for said gears.

5. 2. In a ditching machine, a cutting wheel comprising peripherally disposed ditching members and opposed annularly toothed members on which the ditching members are secured, drive gears meshing with the 10 respective toothed members, said gears being relatively rotatable, and differential means for driving said gears.

3. In a ditching machine, a frame, a cutting wheel mounted therein, oppositely disposed rims secured to the side edges of the wheel, a pair of gears in driving relation to the respective rims, a pair of rotatable members on which the respective driving gears are removably secured, and differential 20 means for driving said rotatable members.

4. In a ditching machine, a cutting wheel having oppositely disposed rims secured to the side edges thereof, two axially aligned 25 rotatable members independently mounted and geared to the respective rims, and differential means for driving said rotatable members.

5. In a ditching machine, a cutting wheel 30 having oppositely disposed rims secured to the side edges thereof, a shaft parallel to the axis of the rims, a pair of sleeves mounted for independent rotation on said shaft, gearing connecting the sleeves individually 35 to the respective rims, and differential means for rotating said sleeves.

6. In a ditching machine, a frame, a cutting wheel mounted therein, oppositely disposed rims secured to the side edges of the 40 wheel, a pair of axially aligned sleeves journaled in said frame, a shaft mounted in said sleeves, the sleeves being rotatable with respect to the shaft, each sleeve having a non-circular portion on which a gear is secured, 45 each gear having an independent driving relation to the corresponding rim, differential gearing, and operative connections from said differential gearing to the respective sleeves.

50. 7. In a ditching machine, a frame, a cutting wheel mounted therein, oppositely disposed rims secured to the side edges of the wheel, a pair of axially aligned members independently journaled in the frame and 55 each having a noncircular portion, gears mounted on the noncircular portions and in

driving relation to the respective rims, means for securing said gears against movement lengthwise of said noncircular portions, said means being adjustable to accommodate the gears to cutting wheels of different widths, and differential means for driving said axially aligned members. 60

8. In a ditching machine, a frame, a cutting wheel mounted therein, oppositely disposed rims secured to the side edges of the wheel, a shaft, a pair of sleeves in which the shaft is mounted, said sleeves being independently journaled in the frame, each sleeve having a noncircular portion, a gear 70 mounted on said noncircular portion and in driving relation to the corresponding rim, a split collar removably secured to the gear, said sleeve having a number of peripheral channels in which the collar may be selectively mounted so that the gears may be adjusted toward or away from each other to 75 accommodate them to cutting wheels of different widths, and differential means for driving said sleeves. 80

9. In a ditching machine, a cutting wheel having oppositely disposed rims secured to the side edges thereof, a shaft parallel to the axis of the rims, a pair of sleeves mounted for independent rotation on said shaft, gearing connecting the sleeves individually to the respecting rims, each of said sleeves having a peripheral flange near one end with a gear bolted to said flange, and differential means 85 for driving the last mentioned gears. 90

10. In a ditching machine, a frame, a cutting wheel mounted thereon, oppositely disposed rims secured to the side edges of the wheel, a shaft, a pair of sleeves in which said shaft is mounted, said sleeves being independently journaled in the frame, each sleeve having a noncircular portion with a gear mounted thereon and in driving relation to the corresponding rim, a split collar 95 removably secured to each of said gears, each sleeve having a number of peripheral channels in which the collar may be selectively mounted so that the gears may be adjusted toward or away from each other to accommodate them to cutting wheels of different widths, each sleeve having a peripheral flange near its outer end, gears bolted to the respective flanges, and differential means for driving said last mentioned gears. 100

In testimony whereof, I have hereunto signed my name to this specification. 105

CHARLES L. GEORGE.
